PORTABLE STEREOGRAPHIC PHONOGRAPH

Frank A. Hinnens, Rockville Centre, N.Y.

Application October 1, 1958, Serial No. 52,827

Term of patent 14 years

(Cl. D56—4)

Fig. 1 is a front perspective view of the portable stereophonic phonograph showing my new design;

Fig. 2 is a rear elevational view thereof;

Fig. 3 is a left side elevational view thereof; and

Fig. 4 is a bottom plan view thereof.

In Figs. 1, 3 and 4 the parallel shading lines do not represent any specific colors, but designate contrast of colors only.

I claim:

The ornamental design for a portable stereophonic phonograph, as shown and described.
